CLAIM

We claim the ornamental design for a strap component for a fluid delivery apparatus, as shown and described.

DESCRIPTION

FIG. 1 is a perspective view of a strap component for a fluid delivery apparatus of our new design.

FIG. 2 is another perspective view thereof.

FIG. 3 is a top plan view thereof.

FIG. 4 is a bottom plan view thereof.

FIG. 5 is a left side view thereof.

FIG. 6 is a right side view thereof.

FIG. 7 is a back elevation view thereof; and,

FIG. 8 is a front elevation view thereof.

The dashed broken lines depict portions of the strap component for a fluid delivery apparatus that form no part of the claimed design.
